UNITED STATES PATENT OFFICE.

ETIENNE FAJON, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,903, dated May 15, 1883.

Application filed April 6, 1883. Term of patent 3½ years.

To all whom it may concern:

Be it known that I, ETIENNE FAJON, of Boston, in the county of Suffolk and State of Massachusetts, have invented a new and original 5 Design for Carpets, of which the following is a specification.

The nature of my design is fully shown in the accompanying photographic illustration.

The design is composed of the floral and foliage ornamentation and the architectural and other figures, as shown.

I claim—

The design for a carpet, substantially as shown and described.

In testimony whereof I have signed my name to this specification, in the presence of two 15 subscribing witnesses, this 30th day of March, 1883.

ETIENNE FAJON.
